CLAIM

The ornamental design for a self-adhesive multi-layer sealing strip, as shown and described.

DESCRIPTION

FIG. 1 is a top perspective view of a self-adhesive multi-layer sealing strip showing our new design;

(Continued)

FIG. 2 is a bottom perspective view thereof;
FIG. 3 is a top plane view thereof;
FIG. 4 is a bottom plane view thereof;
FIG. 5 is a left side elevation view thereof, the right side being a mirror image;
FIG. 6 is a front elevation view thereof;
FIG. 7 is a rear elevation view thereof;
FIG. 8 is an exploded view thereof;
FIG. 9 is a perspective view of the self-adhesive multi-layer sealing strip of FIG. 1 in an alternate multi-strip sheet configuration;
FIG. 10 is a top plane view thereof;
FIG. 11 is a bottom plane view thereof;
FIG. 12 is a left side elevation view thereof, the right side being a mirror image;
FIG. 13 is a front elevation view thereof;
FIG. 14 is a rear elevation view thereof;
FIG. 15 is an exploded view thereof;
FIG. 16 is a perspective view of the self-adhesive multi-layer sealing strip of FIG. 1 showing a bottom-liner layer in the process of being removed therefrom;
FIG. 17 is a perspective view of the self-adhesive multi-layer sealing strip of FIG. 1 installed on a facemask with the a top-liner layer in place; and
FIG. 18 is a perspective view of the self-adhesive multi-layer sealing strip of FIG. 17 installed on a face mask and showing the top-liner layer in the process of being removed therefrom;
FIG. 19 is a perspective view of the self-adhesive multi-layer sealing strip of FIG. 1 installed on an alternative facemask and with the top-liner layer removed;
FIG. 20 is a top perspective view of an alternate embodiment of the self-adhesive multi-layer sealing strip of FIG. 1;
FIG. 21 is a bottom perspective view thereof;
FIG. 22 is a top plane view thereof;
FIG. 23 is a bottom plane view thereof;

FIG. 24 is a left side elevation view thereof, the right side being a mirror image;
FIG. 25 is a front elevation view thereof;
FIG. 26 is a rear elevation view thereof;
FIG. 27 is an exploded view thereof;
FIG. 28 is a perspective view of the self-adhesive multi-layer sealing strip of FIG. 20 in an alternate multi-strip sheet configuration;
FIG. 29 is a top plane view thereof;
FIG. 30 is a bottom plane view thereof;
FIG. 31 is a left side elevation view thereof, the right side being a mirror image;
FIG. 32 is a front elevation view thereof;
FIG. 33 is a rear elevation view thereof;
FIG. 34 is an exploded view thereof;
FIG. 35 is a perspective view of the self-adhesive multi-layer sealing strip of FIG. 20 showing a bottom-liner layer in the process of being removed therefrom;
FIG. 36 is a perspective view of the self-adhesive multi-layer sealing strip of FIG. 20 installed on a facemask with the a top-liner layer in place;
FIG. 37 is a perspective view of the self-adhesive multi-layer sealing strip of FIG. 36 installed on a face mask and showing the top-liner layer in the process of being removed therefrom; and,
FIG. 38 is a perspective view of the self-adhesive multi-layer sealing strip of FIG. 20 installed on an alternative facemask and with the top-liner layer removed.
The dash dot dash broken lines in FIGS. 20-38 depict the claim boundary and form no part of the claim. The evenly dashed broken lines outside the claim boundary in these figures depict portions of the self-adhesive multi-layer sealing strip that form no part of the claim. FIGS. 9, 10, 11, 15, 28, 29, 30, and 34 show a jagged broken line depicting a symbolic break in length in the article. All other broken lines depict environment and form no part of the claim.
